ATTORNEY

UNITED STATES PATENT OFFICE.

ALEXANDER K. SCHAAP, JR., OF BROOKLYN, NEW YORK, ASSIGNOR TO THE SCHAAP-DURANT CONTROL CORPORATION, OF NEW YORK, N. Y., A CORPORATION OF NEW YORK.

LIQUID-LEVEL GAUGE.

Original application filed February 21, 1923, Serial No. 620,430. Divided and this application filed March 20, 1925, Serial No. 19,474. Renewed February 24, 1927.

This invention relates to indicators, and more particularly to an indicating device operating upon the hydrostatic principle for indicating the liquid content of a tank, or other receptacle.

This application is a division of an application Serial Number 620,430, filed February 21st, 1923.

One of the objects of the invention is to provide in an indicator of the above character new and improved means for rectifying the gauge.

Another object of the invention is to provide an indicating system in co-relation with the suction system usually employed for withdrawing fuel or other liquid from a supply tank, wherein the air utilized in the rectifying operation is entrained in a portion of the withdrawn liquid located in the suction system during the suction operation, whereby when a portion of the liquid containing the entrained air is discharged into the body of liquid in the supply tank, the liberated entrained air will co-operate with the gauge system to rectify the gauge.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawing, the figure illustrates schematically a preferred form of embodiment of my invention.

Referring now to the drawing, the reference character A denotes a liquid fuel supply tank, B the usual vacuum tank, and C the gauge. In practice, in a liquid fuel supply system of the vacuum type, the liquid fuel tank is usually located under the body of the car behind the rear axle; the vacuum tank B at a point under the hood of the automobile above the carburetor, and the gauge C is preferably located on the dash in a position to be observed by the occupant of the driver's compartment of the vehicle.

The function of the vacuum tank B is to draw liquid fuel through the suction conduit 1 from the supply tank, mechanism

such as shown being employed in the vacuum tank to trip or operate valve mechanism when a desired quantity of liquid fuel has been drawn into the vacuum tank, such operation permitting the liquid fuel remaining in the conduit 1 to return by gravity into the liquid supply tank.

The liquid fuel supply tank A is preferably provided with a vent 2 of any suitable type, so as to permit air freely to enter the space 3 above the liquid fuel 4 in the supply tank.

The conduit 1 extends downwardly through the top wall of the liquid fuel supply tank A and has its open end 5 located in proximity to the bottom wall of the tank. In the present instance this conduit 1 extends through a larger conduit 6, which conduit 6 also extends downwardly into the tank and has its lower open end 7 terminating adjacent the bottom wall of the tank, as shown herein, slightly below the lower open end 5 of the conduit 1.

Leading from the air space 3 above the level of the liquid fuel in the supply tank A is a tube 8, said tube in the present instance extending through the wall of the conduit 6 and communicating with the conduit 1. This tube has a restricted cross sectional area as compared with the cross sectional area of the conduit 1, the construction being such that when the vacuum tank B functions to draw liquid fuel from the supply tank A sufficient suction will be produced on the tube 8 to cause air to be drawn into the feed line during the suction flow whereby said air will be entrained in the liquid fuel flowing upwardly through the suction conduit 1. When the above mentioned trip mechanism in the vacuum tank operates to cut off or arrest the suction flow of the liquid fuel through the conduit 1 the liquid fuel remaining in the conduit 1 is permitted to flow by gravity into the liquid supply tank and this recessional flow will induce a slight additional quantity of air through tube 8, which air commingling with the air already taken in on the suction flow, will be discharged through the lower end of the conduit 1 into the body of liquid fuel remaining in the supply tank.

Air thus entrained by the flow in both directions and discharged into the body of liquid

fuel in the supply tank by reason of its buoyancy rises and is received in the conduit 6. At this point it will be noted that only such quantity of air will be received in the conduit 6 as is required to establish or maintain the hydrostatic balance between the body of liquid in the supply tank A and the indicating medium in the gauge C. Thus the gauge will be rectified upon the occasion of each recessional flow of liquid fuel through the conduit 1 into the body of liquid remaining in the supply tank.

The gauge C in the present instance takes the form of a U-shaped tube 9, one leg of which is connected with the pressure conduit 11 leading from the conduit 6. This U-shaped tube contains a liquid indicating medium 12, the rising or falling of which in the leg 13 of said U-shaped tube in combination with a suitable scale (not shown) provides the desired indication of the quantity of fuel remaining in or withdrawn from the supply tank A.

It will accordingly be seen that the construction above set forth attains, among others, all the ends and objects above pointed out in a very simple yet efficient manner.

It will be noted that the suction system and the gauge system while independent instrumentalities are so correlated that the operation of the suction system rectifies the gauge and that the withdrawal of the liquid fuel through the conduit 1 by the operation of the suction system will not in any wise disturb the hydrostatic balance thereby causing a vibration or momentary fluctuation of the indicating medium in the gauge.

As many changes could be made in this construction without departing from the scope of the following claims, it is intended that all matter contained in the above description or shown in the accompanying drawings shall be regarded as illustrative only and not in a limiting sense.

Having thus described my invention what I claim as new and desire to secure by Letters Patent is:

1. In apparatus of the class described, in

combination, a liquid containing tank, a pressure tube extending into the liquid in the tank and having an open lower end disposed near the bottom of the tank, a suction tube extending down into the liquid in the tank and terminating in an open lower end adjacent the bottom of the tank and adjoining the open lower end of the pressure tube, means for establishing restricted communication between the suction tube and the air, means for causing a flow of liquid from the tank and for permitting a return flow into the tank through said suction tube so that air will be drawn into said suction tube through said restricted communicating means on flow of the liquid therethrough in both directions and be thereby entrained in the liquid in the suction tube and then be discharged from the lower end thereof when liquid returns to the tank through said suction tube, the open lower ends of the suction and pressure tubes being so related that upon such discharge from the suction tube the air thereby released will rise into the pressure tube and pressure actuated means connected with said pressure tube for indicating the liquid in the tank.

2. In a device of the class described, a liquid containing tank, a pressure tube entered through the top of the tank into the liquid therein, a liquid withdrawing tube extending down through the pressure tube into the liquid in the tank, an air inlet tube of restricted size extending through the side of the pressure tube and opening into the liquid withdrawal tube so that upon flow of liquid through the liquid tube in either direction air will be entrained in such liquid and upon flow through the tube into the tank such air will be released at the lower end of the same, the pressure tube having an open lower end surrounding the lower end of the liquid tube to thereby receive the air thus released from the liquid tube and a pressure gauge in communication with said pressure tube.

In testimony whereof, I affix my signature.

ALEXANDER K. SCHAAP, JR.
